UNITED STATES PATENT OFFICE

EDGAR ANSTETT, OF CHICAGO, ILLINOIS, ASSIGNOR TO RICHARD GROETCHEN, OF CHICAGO, ILLINOIS

LAP

Application filed April 15, 1929. Serial No. 355,064.

This invention relates to a lap. It relates generally to a lapping, finishing or abrading tool. It has for one object to provide a lapping member which is adapted for use about 5 a relatively permanent tool in connection with which the lapping member may be removably mounted. Another object is to provide a relatively temporary lapping member for use upon a relatively permanent holding 10 tool in which the tool is of a harder material than the lap. Another object is to form the lap itself so that its operation serves to distribute and convey abrasive or other lubricant along the surface being acted upon. 15 Other objects will appear from time to time in the course of the specification and claims.

The invention is illustrated more or less diagrammatically in the accompanying drawings wherein—

20 Figure 1 is a side elevation of the lap in position with parts in section;

Figure 2 is a side elevation of the tool;

Figure 3 is a side elevation of the lap removed from the tool;

25 Figure 4 is a transverse cross section taken on line 4—4 of Figure 1 shown on an enlarged scale;

Figure 5 is a transverse section taken on line 5—5 of Figure 3 shown on an enlarged 30 scale;

Like parts are indicated by like characters throughout the specification and drawings.

A is a tool holder in which a tool A¹ may be removably positioned. The tool is provided with a slot A², a relatively large collar A³ and a smaller collar A⁴ between which a groove or depression A⁵ is formed.

The collar A⁴ may act as a stop to stop or limit upward movement of the lap which is 40 to be put on the tool.

B is a piece of material provided with a perforation B¹ in which the lap is shown as positioned for work.

C is the lap. As shown it is formed of a 45 strip of material, preferably metal, bent into the form of a helix. At its upper end it is reduced as at C¹ and this reduced portion is inwardly bent at C². At its lower end the lap portion is reduced as at C³ and it may be 50 provided with an inwardly bent end C⁴,

When the tool is used it is normally used with some sort of abrasive or other lubricant. This material, D, is indicated diagrammatically as lying within the slot A² and it is shown also at D¹ as lying within the helical 55 groove formed by the lap member itself.

It will be obvious that while I have shown and described an operative device, many changes may be made in the size, shape, relation, proportion and distribution of parts 60 without departing materially from the spirit of my invention, and I wish therefore my description and drawings to be considered as in a large measure diagrammatic.

The use and operation of this invention are 65 as follows:

The carrying tools A¹ may be made in any suitable variety of sizes and for these sizes appropriate lapping members C are formed. When a perforation is to be lapped, a tool of 70 the appropriate size is chosen and the corresponding lap is fitted upon it. The tool with the lap upon it is then inserted in a perforation and lubricant is supplied. Ordinarily it will be supplied to the slot and it will run 75 down the slot and from this will flow out into the spaces formed by the helical lapping member and will thus conform to the outside or working face of that member. The tool is then set in motion and carries with it the lap 80 which has a lapping action. The lubricant or abrasive flows out as above described to the outer or working face of the lap and contacts the wall of the perforation which is being lapped. The helical groove formed by 85 the lap itself under some circumstances has a conveying effect, acting like a screw conveyor and tending to move the abrasive along the working surface. This is not an essential feature of the invention, but under some 90 circumstances it is important.

I claim:

1. In a lapping device, a main supporting part provided with an opening, and an auxiliary lapping part adapted for removable 95 mounting upon said main part, said auxiliary part shaped in a generally helical form and provided with a portion adapted to engage the opening in said main member and being generally self supporting. 100

2. In a lapping device, a main supporting part provided with an opening in the form of a slot formed in it, and an auxiliary lapping part adapted for removable mounting upon said main part, said auxiliary part shaped in a generally helical form and provided with a portion adapted to engage the opening in said main member and formed of such material as to be generally self-supporting.

3. In a lapping device, a main supporting part provided with a generally axial opening in the form of a slot formed in it, and an auxiliary lapping part adapted for removable mounting upon said main part, said auxiliary part shaped in a generally helical form and provided with a portion adapted to engage the opening in said main member and formed of such material as to be generally self-supporting.

4. In a lapping device, a main supporting part provided with an opening, and an auxiliary lapping part adapted for removable mounting upon said main part, said auxiliary part being of a material softer than the main part shaped in a generally helical form and provided with a portion adapted to engage the opening in said main member and formed of such material as to be generally self-supporting.

5. In a lapping device, a main supporting part provided with an opening and having a lap limit and an auxiliary lapping part adapted for removable mounting upon said main part, said auxiliary part shaped in a generally helical form to provide a helical groove throughout its length and provided with a portion adapted to engage the opening in said main member and formed of such material as to be generally self supporting.

6. In a lapping device, a main supporting part provided with an opening and having a lap limit and an auxiliary lapping part adapted for removable mounting upon said main part, said auxiliary part shaped of a single piece in a generally helical form to provide a helical groove throughout its length and provided with a portion adapted to engage the opening in said main member and formed of such material as to be generally self supporting.

7. In a lapping device, a main supporting part provided with an opening, and having a lap limit and an auxiliary lapping part adapted for removable mounting upon said main part, said auxiliary part shaped of a single piece in a generally helical form and provided with an inbent portion adapted to engage the opening in said main member and formed of such material as to be generally self supporting.

8. In a lapping device, a main supporting part provided with an opening in the form of a slot formed in it, and having a laterally extending lap limit, and an auxiliary lapping

part adapted for removable mounting upon said main part, said auxiliary part shaped of a single piece in a generally helical form and provided with a portion adapted to engage the opening in said main member and formed of such material as to be generally self supporting.

9. In a lapping device, a main supporting part provided with an opening in the form of a slot formed in it, and having a laterally extending limit in the form of a flange, and an auxiliary lapping part adapted for removable mounting upon said main part, said auxiliary part shaped in a generally helical form to provide a helical groove throughout its length, and provided with an inbent portion adapted to engage the opening in said main member and formed of such material as to be generally self supporting.

10. In a lapping device, a main supporting part provided with an opening in the form of a slot formed in it, and having a laterally extending limit in the form of a flange, and an auxiliary lapping part adapted for removable mounting upon said main part, said auxiliary part shaped of a single piece in a generally helical form to provide a helical groove throughout its length and provided with an inbent portion adapted to engage the opening in said main member and formed of such material as to be generally self supporting.

11. In a lapping device, a main supporting part provided with a generally axial opening in the form of a slot formed in it, and having a laterally extending limit in the form of a flange, and an auxiliary lapping part adapted for removable mounting upon said main part, said auxiliary part being of a material softer than the main part, shaped of a single piece in a generally helical form to provide a helical groove throughout its length, and provided with an inbent portion adapted to engage the opening in said main member and formed of such material as to be generally self supporting.

12. In combination in an abrasive device, a tool holder provided with a plurality of outwardly extending flanges, an opening and a metallic tool formed of a single member shaped in a generally helical arrangement and provided at one end with a reduced inbent portion adapted to be received within the opening in the tool holder, one of said flanges adapted to serve as a stop for said tool.

13. In combination in an abrasive device, a tool holder provided with a plurality of outwardly extending flanges, an opening and a metallic tool formed of a single member shaped in a generally helical arrangement and provided at one end with a reduced inbent portion adapted to be received within the opening in the tool holder and provided at its other end with a reduced inwardly bent portion adapted to contact the tool hold-

er one of said flanges adapted to serve as a stop for said tool.

14. In combination in an abrasive device, a tool holder provided with a plurality of outwardly extending flanges, an opening in the form of a slit extending longitudinally throughout a portion of the tool holder, and a metallic tool formed of a single member shaped in a generally helical arrangement and provided at one end with a reduced inwardly bent portion adapted to be received within the opening in the tool holder one of said flanges adapted to serve as a stop for said tool.

15. 15. In combination in an abrasive device, a tool holder provided with a plurality of outwardly extending flanges, an opening in the form of a slit extending longitudinally throughout a portion of the tool holder, and a metallic tool formed of a material softer than the holder, formed of a single member shaped in a generally helical arrangement and provided at one end with a reduced inwardly bent portion adapted to be received within the opening in the tool holder and provided at its other end with a reduced inwardly bent portion adapted to contact the tool holder one of said flanges adapted to serve as a stop for said tool.

30 Signed at Chicago, county of Cook and State of Illinois, this 6th day of April, 1929.

EDGAR ANSTETT.
